(57) **CLAIM**

The ornamental design for a combined carpenter's pencil and level, as shown and described.

DESCRIPTION

FIG. 1 is a perspective view of a first embodiment of a combined carpenter's pencil and level;

FIG. 2 is a first side elevational view of a combined carpenter's pencil and level;

FIG. 3 is a second side elevational view of a combined carpenter's pencil and level;

FIG. 4 is a top plan view of a combined carpenter's pencil and level;

FIG. 5 is a bottom plan view of a combined carpenter's pencil and level;

FIG. 6 is a front end view of a combined carpenter's pencil and level;

FIG. 7 is a rear end view of a combined carpenter's pencil and level;

FIG. 8 is a perspective view of a second embodiment of a carpenter's pencil and level;

FIG. 9 is a first side elevational view of a combined carpenter's pencil and level;

FIG. 10 is a second side elevational view of a combined carpenter's pencil and level;

FIG. 11 is a top plan view of a combined carpenter's pencil and level;

FIG. 12 is a bottom plan view of a combined carpenter's pencil and level;

FIG. 13 is a front end view of a combined carpenter's pencil and level;

FIG. 14 is a rear end view of a combined carpenter's pencil and level;

FIG. 15 is a perspective view of a third embodiment of a combined carpenter's pencil and level;

FIG. 16 is a first side elevational view of a combined carpenter's pencil and level;

FIG. 17 is a second side elevational view of a combined carpenter's pencil and level;

FIG. 18 is a top plan view of a combined carpenter's pencil and level;

FIG. 19 is a bottom plan view of a combined carpenter's pencil and level;

FIG. 20 is a front end view of a combined carpenter's pencil and level; and,

FIG. 21 is a rear end view of a combined carpenter's pencil and level.
